Des. 236,306
Patented Aug. 19, 1975

236,306

MERCHANDISE DISPLAY STAND

Arthur E. Spieler, Floral Park, N.Y., assignor to Jonathan Leigh Inc., New York, N.Y.

Filed Apr. 17, 1974, Ser. No. 461,776

Term of patent 14 years

Int. Cl. D20—02

U.S. Cl. D6—85

FIG. 1

FIG. 5

FIG. 6

FIG. 1 is a perspective view of a merchandise display stand showing my new design;

FIG. 2 is a front view;

FIG. 3 is a side view;

FIG. 4 is a rear view;

FIG. 5 is a top view; and

FIG. 6 is a bottom view.

The side of the display stand not shown is a mirror image of the side shown.

I claim:

The ornamental design for a merchandise display stand, substantially as shown and described.
